UNITED STATES PATENT OFFICE.

RALPH DWIGHT ERNEST, OF ANN ARBOR, MICHIGAN.

REISSUED

AUTOMATIC STARTER AND CONTROLLER.

1,273,798.

Specification of Letters Patent. Patented July 23, 1918.

Application filed October 19, 1916. Serial No. 126,478.

To all whom it may concern:

Be it known that I, RALPH D. ERNEST, a citizen of the United States, and a resident of Ann Arbor, in the county of Washtenaw and State of Michigan, have invented a certain new and useful Improvement in Automatic Starters and Controllers, of which the following is a specification.

My invention relates to improvements in automatic starters and controllers, and it consists in the combinations, constructions and arrangements herein described and claimed.

An object of my invention is to provide a device to be used in connection with gas, gasolene, or oil driven electric generating sets, the purpose being to operate the said generating sets in such a way as to provide current at the proper voltage when there is a demand for the same, and to immediately stop the generating of current when there is no demand for power.

A further object of my invention is to eliminate the necessity for the use of a storage battery, storage batteries being expensive, inefficient, and short-lived.

Other objects and advantages will appear in the following specification, and the novel features of the invention will be pointed out in the appended claims.

My invention is illustrated in the accompanying drawing, which is a diagrammatic view of the various parts and their circuit connections.

In carrying out my invention, I provide a generator A which may be a 110 volt direct current shunt or compound wound generator driven by, and direct connected to a single cylinder gas engine B. A 12 volt starter C is geared direct to the common shaft 1. A 12 volt starting battery D is provided to furnish energy for starting. At E, I have shown a single pole, solenoid operated circuit breaker.

In addition to the above apparatus, I provide three relays, X, Y, and Z. Three switches are also provided, as shown at S¹, S² and S³, respectively, the latter being a time retarded switch.

Relay X controls the operation of the circuit breaker, as will be explained later. It is a potential relay and operates at a few volts under normal working voltage, which in this case, is about 105 volts. Relay Y is a current relay in series with the generator

mains. It controls together with the auxiliary switch S³, the ignition circuit to the engine. This relay is arranged to open when the current flowing in the generator mains falls below a predetermined minimum, thus opening the ignition circuit. The relay Z is a current relay in series with the switch S¹, the battery, and the mains L and L^x, and is used to control the starting circuit.

The operation of the device will best be understood by taking up the steps in the order in which they actually occur. Let us assume that the generator is standing still, the relays X, Y and Z are open. The circuit breaker E, as will be seen from the drawing, is in such position as to close the switches S¹ and S³, and to open the switch S². There is therefore a 12 volt pressure on the circuit mains L and L^x. Suppose now a 25 watt lamp, such as that shown at W is switched on, this will cause a current to flow from the battery D through wire 2, relay Z, wire 3, switch S¹, wire 4, through one of the mains L, then through the lamp W to the other main L^x and back to the battery by wire 5.

The operation of the relay Z will close the circuit from the battery D through the starter C, wire 7, contacts of the relay Z through the wire 8 back to the battery. The ignition circuit will also be closed, the current flowing from the battery D through wire 6, wire 9, primary P of the induction coil, wire 10, wire 11, switch S³, wire 12, wire 7, contacts of relay Z, wire 8, back to the battery.

The engine is now started. As speed increases, the voltage of the generator will increase, exerting a pressure on relay X which will operate at about 105 volts. The closing of the contacts of the relay X energizes the coil of the circuit breaker over the following path; from battery D, through wire 13, contacts of the relay X, coils of the circuit breaker E and back by wire 14 to the battery. The operation of the circuit breaker in closing, opens the auxiliary switches S¹ and S³, and closes the auxiliary switch S². Switch S³ is slightly retarded due to its time element, in order to allow time to energize the relay Y, by the current flow due to the closing of the circuit breaker. The auxiliary switch S³ is thus open during normal running, which gives relay Y complete control over the ignition

circuit. The relay Z is protected from the generator voltage by the opening of the auxiliary switch S¹. The closing of the auxiliary switch S² closes the circuit between the starting motor-generator and the battery, allowing the starting motor, now a generator, to charge the battery in addition to furnishing current for ignition and for operating the circuit breaker solenoid.

10 Let us now consider the effect when all the lamps are turned off, causing the current in the generating circuit to decrease to a minimum. Relay Y having no current to energize it will open and break the ignition circuit, causing the engine to stop. As the speed falls off, the generator voltage will fall off and at 105 volts, the circuit breaker will open and will restore the auxiliary switch S¹ to a closed position, thereby completing the circuit through the relay Z as far as the circuit mains, ready for starting. The opening of the circuit breaker opens auxiliary switch S² before the starting motor-generator voltage falls low enough to begin to take power from the battery. The auxiliary switch S³ tends to close, but is retarded in doing so long enough to allow the engine to stop before closing, as otherwise ignition would be restored and the engine would start up again.

20 25 30

It will be seen that the operation of the generating sets is controlled by the condition of the load on the circuit mains, and obeys the call for energy instantly. One has only to close the switch to cause the generator to be started and furnish the power required, and on the other hand, one has only to open the switch to stop the whole system.

I claim:

1. The combination of an internal combustion engine, having electric igniters, an electric starter for said engine, a generator driven by the engine, a battery, a main power or lighting circuit, said battery having normal connections with said main circuit, a relay operated by the battery current for controlling the ignition circuit and the electric starter, a relay in the main circuit for opening or closing the ignition circuit, a circuit breaker for opening and closing said main circuit, a switch for controlling the battery circuit, a quick-acting switch and a time retarded switch for partly controlling the ignition circuit, all of said switches being operated by said circuit breaker.

2. The combination of an internal combustion engine, having electric igniters, an electric starter for said engine, a generator driven by the engine, a battery, a main power or lighting circuit, said battery having normal connections with the said main circuit, a relay operated by the battery current for controlling the ignition circuit and the electric starter, a relay in the main circuit for opening and closing said ignition circuit, a switch for controlling the battery circuit, a quick-acting switch and a time retarded switch for partly controlling the ignition, all of said switches being operated by said circuit breaker, and a relay in the main circuit and operated at a predetermined voltage for controlling the circuit breaker of the generator.

RALPH DWIGHT ERNEST.
